CUTTER HEAD GUARD FOR SHAPING MACHINES

Samuel I. Hartzell and Lambert Franke,
St. Louis, Mo.

Application September 17, 1934, Serial No. 744,276

5 Claims. (Cl. 144—251)

This invention relates to cutter head guards for shaping machines, and has for its main object to provide a cutter head guard of simple design that moves automatically into an inactive or inoperative position when the work is being fed to the cutter head, and at the completion of the cutting operation, returns automatically to its normal position, wherein it acts as a shield or housing for the knives or other shaping devices of the machine.

Another object is to provide a cutter head guard of the kind mentioned, that can be adjusted easily to adapt it to cutter heads of different diameters and also to provide for variations in the distance that the work overhangs or projects beyond the edge of the jig to which the work is fastened. Other objects and desirable features of our invention will be hereinafter pointed out.

Figure 1 of the drawings is a side elevational view of my improved cutter head guard, showing the shield or housing member in its normal operative position.

Figure 2 is a top plan view of the apparatus shown in Figure 1.

Figure 3 is a side elevational view, showing the shield or housing member in its raised or inactive position; and

Figure 4 is a horizontal sectional view, taken on the line 4—4 of Figure 3.

In the accompanying drawings which illustrate the preferred form of our invention, A designates the cutter head of a wood shaping machine, which cutter head may be of any suitable or preferred construction, B designates a member that acts as a guard, shield or housing for the cutter head, and C designates the work table of the machine. The guard or housing member B is herein illustrated as consisting of a semi-circular-shaped shell, disposed vertically in front of the cutter head and arranged so that it normally incloses or partially incloses said cutter head, as shown in Figure 1. During the operation of feeding the work x to the cutter head the guard B moves automatically into an elevated or inactive position, as shown in Figure 3, so as to permit the work to be moved into sufficiently close proximity to the cutter head to cause the knives of same to act on the work. At the completion of the cutting operation, the guard B returns automatically to its normal position shown in Figure 1. Various means may be used to support and actuate the guard B, but we prefer to mount the guard B slidingly on a vertically-disposed guide 1 attached to a horizontally-disposed support 2 car-

ried by an upright 3 which projects upwardly from the table of the machine. The semi-circular-shaped shell that constitutes the guard B is provided at its upper end with a bearing 4 that slides on the guide 1, the hole in said bearing through which said guide passes having walls of sufficient area to effectively hold the guard B in a vertical position and preventing it from tilting or wobbling.

The actuating mechanism for the guard B preferably comprises a lever D carried by the upright 3 and pivotally connected to the bearing 4 on the guard or housing member B, a reciprocating slide E arranged above the work table and adapted to be moved in one direction by pressure exerted on the front end of said slide by the jig y which carries the work, and a lifter F interposed between the slide E, and lever D, and provided at its lower end with a roller 5 that co-acts with a cam or inclined surface 6 on the top side of the slide E. Said slide is moved in the reverse direction or restored to its normal position by a weight, spring or similar means, and the guard B and lever D are so proportioned that gravity will cause said guard to move downwardly back to its former position as soon as the pressure of the jig on the front end of the slide E is removed.

As shown in the drawings, the lever D is pivotally attached at 7 to the upper end of the upright 3, and said lever is provided at its front end with a yoke 8 that straddles the bearing 4 and is pivotally connected to same by laterally-projecting pins 9 on said bearing which project into elongated slots 10 in the side pieces of the yoke 8. In order to assist in the upward movement of the guard B, a counterbalancing weight 11 is adjustably mounted on the opposite end of the lever D. The slide E, previously mentioned, is provided at its front end with a yoke-shaped portion 12, that is engaged by the jig y during the operation of feeding the work to the cutter head, said yoke-shaped portion 12 being slidably mounted above the collar 13 on the table C of the machine, up through which the supporting shaft of the cutter head projects. At the front end of said yoke-shaped portion 12 is a convexed surface that is used as a guide for the jig y during the cutting operation. Consequently, when the jig y with the work x thereon is moved over the table of the machine towards the cutter head A, the guard B starts to move upwardly as soon as the work carrying jig engages the front end of the slide E, and continues to move upwardly into the position shown in Figure 3 while the work is being brought within range of the knives.

or shaping devices on the cutter head. In feeding the work to the cutter head the operator merely moves the jig *y* rearwardly until the convexed front end portion of the slide *E* comes into vertical alignment with the curved outer edge of the collar *13* on the table of the machine, and during the shaping operation the jig *y* is held in engagement with both the collar *13* and the convexed front end of the slide *E*, with the result that the 10 guard *B* will be maintained in its elevated or inactive position during the cutting operation. As soon as the operator releases the pressure on the front end of the slide *E*, said slide moves forwardly under the influence of one or more springs 15 *14* or an equivalent means attached to the rear end of same, and the guard *B* drops downwardly to its normal operative position, the shock on the upper end portion of the guard *B* being absorbed when said guard reaches its extreme low- 20 ermost position by means of a buffer *15* attached to the supporting member *2*.

From the foregoing it will be understood that our improved cutter head guard is entirely automatic in its operation, insofar as the engagement of the work carrying jig *y* with the front end of the slide *E* during the operation of feeding the work to the cutter head, causes the guard *B* to move upwardly high enough to clear or expose the cutter head, and at the completion of the 25 shaping operation, when the rearward pressure on the front end of the slide *E* is removed, the guard *B* drops back automatically to its normal position. In the form of our invention herein illustrated the slide *E* is guided partly by the upright *3* that has an opening in same through which the rear end portion of the slide *E* projects, and partly by guide pins *16* on the collar *13* that project upwardly through elongated slots 30 *17* in the side pieces of the yoke-shaped front end portion *12* of said slide.

The lifter *F*, previously referred to, is arranged vertically on the front side of the upright *3* and is retained in position by a bearing or strap *18* on said upright. Said lifter passes upwardly 45 through a slot or opening in the horizontally-disposed supporting member *2*, and at the extreme upper end of said lifter is a roller *19* that bears against the underside of the lever *D*. In order to securely hold the lifter *F* in parallel relation 50 with the upright *3*, the supporting member *2* is provided with a roller *20*, shown in dotted lines in Figures 1 and 3, that bears against the front side of said lifter. Any means may be used to arrest and limit the forward movement of the 55 slide *E* when the guard *B* is returning to its normal position, the means herein illustrated for this purpose consisting of a stop *21* on the rear end portion of the slide *E*, which strikes against the roller *5* during the forward movement of the 60 slide, said stop being provided with a concaved front edge that merges into the cam surface *6* and co-acts with same to form a notch in the top side of the slide in which the roller *5* is positioned when the guard or housing member *B* is 65 in its normal operative position.

In order that the guard *B* and its actuating apparatus may be used with cutter heads of different diameters, the upright *3* is attached to a base plate *22* that is adjustably mounted on the 70 table *C* of the machine in such a way that said upright can be adjusted towards and away from the cutter head *A*. Thus, as shown in Figures 2 and 4, the base plate *22* is retained in position by means of clamping screws *23* on the table of the 75 machine that pass through elongated slots *24* in

the base plate. When the screws *23* are released, the upright *3* and all the parts sustained or carried by same may be moved forwardly or rearwardly to vary the distance between the guard *B* and the axis of rotation of the cutter head. We also prefer to construct the slide *E* in such a way 5 that the front end portion *12* of same may be adjusted longitudinally to vary the length of the slide, and in the form of our invention herein illustrated, this is attained by clamping the yoke-shaped member *12* to the rear end portion of the slide, by means of clamping screws *25* that pass through elongated slots *26* in the side piece of the yoke-shaped member *12*.

Having thus described our invention, what we 15 claim as new and desire to secure by Letters Patent is:

1. A cutter head guard for shaping machines, comprising a guard member that normally houses or shields the cutter head, a lever for raising and lowering said guard member, a horizontally-movable slide arranged above the work table of the machine in the path of movement of the work and adapted to move bodily with the work under the influence of the pressure employed to feed the work to the cutter head, and a mechanical means operated by said slide for moving and controlling the position of said lever. 20

2. A cutter head guard for shaping machines, comprising a vertically-movable guard member arranged so as to normally shield or guard the cutter head of the machine, a standard that projects upwardly from the table of the machine, a lever on said standard for raising and lowering said guard member, a horizontally-movable slide arranged above the work table of the machine in the path of movement of the work and adapted to move bodily with the work under the influence of the pressure employed to feed the work to the cutter head, and a vertically-movable lifter 30 actuated by said slide for moving and controlling the position of said lever. 35

3. A cutter head guard for shaping machines, comprising a vertically-movable guard member that normally shields or houses the cutter head of the machine, a counterweighted lever for raising and lowering said guard member, a horizontally-movable slide arranged above the work table of the machine in the path of movement of the work and adapted to move bodily with the work under the influence of the pressure employed to feed the work to the cutter head, a lifter interposed between said slide and lever, and a cam on said slide for actuating said lifter. 45

4. A cutter head guard for shaping machines, comprising a member for housing or shielding the cutter head, a standard on the table of the machine, a vertically-disposed guide carried by said standard, a bearing on said housing member slidably mounted on said guide, a lever on said standard pivotally connected to said bearing for raising and lowering the housing member, a horizontally-movable slide arranged above the work table of the machine in the path of movement of the work and adapted to move bodily with the work under the influence of the pressure employed to feed the work to the cutter head, and a vertically-movable lifter on said standard interposed between said lever and slide and provided with a roller that co-acts with an 60 inclined surface on said slide. 65

5. A cutter head guard for shaping machines, comprising a member that houses or shields the cutter head of the machine, actuating lever for raising and lowering said housing member, a 75

horizontally-movable slide arranged above the work table of the machine in the path of movement of the work and adapted to move bodily with the work under the influence of the pressure employed to feed the work to the cutter head, said slide being provided at its front end with an adjustable part that is adapted to be en-

gaged by the jig to which the work is attached, a return spring for said slide, and a mechanical means for transmitting movement from said slide to said lever.
